CONTAINER BUNG

William Lauber, Milwaukee, Wis., assignor of
one-half to Henry T. Klinkerfues, Milwaukee,
Wis.

Application August 16, 1935, Serial No. 36,503

16 Claims. (Cl. 217—110)

This invention relates to improvements in container bungs.

It has for many years been common practice in the brewing industry to use a wooden bung as a closure for the brewmaster's filling opening. Wooden bungs, however, have to be driven into the bung opening and are frequently broken by the mallet resulting in waste of both time and material. Furthermore, latent defects in the wood not uncommonly result in leakage. In addition, when the empty barrels are returned to the brewery, the bung must be bored or chipped out with the result that fragments of the wood often fall into the barrel and remain there after washing.

It is an object of the present invention to provide an inexpensive metal bung adapted to overcome the above mentioned objectionable features. While in the past it has been proposed to employ metal bungs acting in conjunction with rubber sleeves or washers to seal the opening, these devices have never been commercially satisfactory as the rubber necessarily comes in contact with the beer and the sulphur contained in the rubber contaminates the beverage. Furthermore, these bungs are not capable of remaining securely in position when subjected to the jolts occurring during the handling and transportation of barrels.

30 A more specific object of the invention is to provide a container bung in which a metal screw coacts with a sleeve of deformable metal to permanently and securely seal the barrel opening.

A further specific object of the invention is to provide a device of the class described which may include a shield for the deformable metal to prevent the latter from coming in contact with the beer and also to prevent any leakage of beer through the screw threads.

40 A further object of the invention is to provide a container bung which can be removed, when the empty barrel is returned to the brewery, by means of a special pulling tool, there being no possibility of any foreign matter falling into the barrel during such removal.

50 A further object of the invention is to provide a metal container bung which is constructed to readily receive a disc label or seal, which label may bear the date of the brew and any desired advertising material, and which further is so held in position as to make it impossible to tamper with the bung without first mutilating the label.

55 A further object of the invention is to provide a metal bung, which, while particularly adapted

for use in connection with beer barrels, is nevertheless susceptible of a wide range of other uses.

With the above and other objects in view the invention consists of the improved container bung and all its parts and combinations as set forth in the claims and all equivalents thereof.

In the accompanying drawing illustrating one complete embodiment of the preferred form of the invention, in which the same reference numerals designate the same parts in all of the views

Fig. 1 is a longitudinal sectional view through the bung opening of a barrel showing the improved bung in position therein before it has been locked in place, the dot-and-dash lines indicating a turning tool cooperating therewith; 15

Fig. 2 is a similar sectional view showing the bung in sealing condition;

Fig. 3 is a plan view of the bung opening with the improved bung in position therein; 20

Fig. 4 is a perspective view of the screw element alone;

Fig. 5 is a perspective view of the improved bung alone in condition for use;

Fig. 6 is a plan view of the bung opening showing a label in position on the bung; and 25

Fig. 7 is a view similar to Fig. 2 showing the special pulling tool in position for removal of the bung from an empty barrel, parts of the tool being broken away and shown in section. 30

Referring more particularly to the drawing, the numeral 8 designates a fragment of a container surrounding the usual bung opening 9. Said opening 9 is fitted with the usual downwardly and inwardly tapered metal bushing 10, which bushing terminates short of the interior of the barrel as at 11. The bushing may further be formed with the usual exterior flange 12.

The improved bung consists of two parts, a screw 13 and a sleeve 14. The screw may be 40 formed of any suitable metal, but is preferably of cast iron or steel. The threads 13' may be either cast thereon or formed on a screw machine. The upper end of the screw is of somewhat less diameter than the lower end thereof to 45 provide sides which are tapered in a reverse direction to the taper of the sides of the bushing. In addition, the lowermost screw thread 15 projects laterally beyond the other screw threads for a purpose to be hereinafter described in detail. 50

The upper end of the screw is provided with an opening of any desired shape for cooperation with a turning tool. In the drawing a circular opening 16 is illustrated which has a laterally extending key slot 17, the opening 16 communi- 55

cating with a larger opening 18 therebelow. It will thus be seen that this opening is adapted to cooperate with a turning tool 19 having a round lower portion 20 formed with a projecting key 21 for cooperation with the key slot 17. The opening 16 may, of course, be rectangular for cooperation with a rectangular end of a different type of turning tool.

After the screw is manufactured the sleeve 14 may be formed by pouring metal around the screw as the core of a mold. The sleeve 14 is preferably formed of lead and has its interior opening tapered to conform to the taper of the screw and formed with threading 22 which conforms 15 with the threading on the screw.

While lead is the preferred material for the sleeve, other deformable metal such as aluminum or tin may be employed.

Inasmuch as some breweries may object to 20 lead coming in contact with the beer, it is preferred to utilize a cup shaped shield 23 on the bottom of the sleeve. This shield is preferably of aluminum foil.

In actual practice, in manufacturing the bung, 25 the aluminum foil is first pressed into the cup shaped form and placed in the bottom of a mold. The screw 13 is then centered within the shield and the lead or other deformable material is poured into the space between the sides of the 30 mold and the screw. This causes the foil shield to be cast into the lead sleeve as an integral part thereof and to be indented into the sides thereof so that the sides of the sleeve, with the shield thereon are flush from top to bottom. While 35 aluminum foil is the preferred material for the shield, other suitable sheet material may be employed. After the bung assemblage has been manufactured as above described, it is preferable to place it in a vibrator to break the adhesion 40 between the screw and the lead so that the screw may be turned in use.

When a barrel is to be sealed, the bung assemblage is dropped into the bushing 12 as shown 45 in Fig. 1 its lower portion projecting below the lower end 11 of the bushing. Next the turning tool 19 is inserted in place and the screw is turned upwardly with respect to the lead sleeve. Due to the taper on the sides of the screw which 50 extends in a reverse direction to the taper of the sides of the bushing 10, and to the fact that the bottom screw thread 15 projects laterally beyond the other screw threads, the result of this upward turning is a deformation of the lower portion of the lead sleeve as shown in Fig. 2 so that the 55 sleeve is pressed tightly against the sides of the bushing and so that its lower portion is flared outwardly to prevent withdrawal of the bung. It will thus be seen that with this method of deforming the lead sleeve, that no jolts however 60 severe can disturb the secure sealing effect. It will further be seen that the foil shield 23 prevents the beverage and gas from coming in contact with the screw and sleeve, and possibly leaking out through the screw threads. The shield 65 may extend any desired distance upwardly on the sleeve, it being merely necessary that it extend sufficiently high to eliminate any possibility of contact of the beverage with the lead sleeve.

A seal or label 24 of card board or the like 70 may be snapped into position on the shoulder 24' of the lead ring as shown in Figs. 2 and 6, and said label may contain the date of the brew and any desired advertising material. Inasmuch as the label fits tightly, access cannot be had to the 75 bung without first mutilating the label.

When the empty barrel is returned to the brewery, a special pulling tool may be employed to remove the bung from the opening. As shown in Fig. 7, the tool may comprise a U-shaped frame 25, the two lower ends 26 of which are 5 adapted to bear on opposite sides of the bushing flange 12. A screw 27 has its upper threaded end projecting loosely through an opening in the top of the frame for the reception of a nut 28. Loosely mounted on a rivet 29 extending through 10 the lower end of the screw 27 is a pair of fingers 30 which are swingable from a compressed position against tapers 31 to the expanded position shown in the figure. The lower ends of the fingers may be recessed as at 32. 15

When the fingers are compressed they may be inserted in the opening 29 of the screw and dropped to the position shown by loosening of the nut 28. When in proper position, a cam or the like 33 is turned by means of a lever 34 to 20 expand the lower ends of the fingers. Next by turning downwardly on the nut 28, the screw 27 and fingers are raised causing the entire bung to be forcibly pulled out of the bung opening. Instead of the cam 33 resilient means may be employed between the fingers to normally hold them in expanded position so that the fingers can be compressed against the tension of the resilient means for insertion, after which they will automatically spring to expanded position. 25

When the bung is removed, the lead ring will, of course, be mutilated. The screw however is in condition for re-use, and the screws may be returned by the brewery to the manufacturer and used as a credit against new bung assemblies. As 35 an alternative the manufacturer of the bungs may furnish only new lead sleeves and separate shields 23 so that the brewer can reassemble his own bungs using the screw portions 13 over and over again. 40

From the above it may be seen that a very simple form of bung has been provided which is highly satisfactory due to the use of distortable metal for the sleeve. This metal is the principal feature of the invention in view of the fact that 45 when distorted by upward turning of the screw, it forms a rigid seal against the side of the bushing and also forms a rigid lock beneath the lower end of the bushing to absolutely prevent loosening or removal without the use of the pulling tool. It will further be seen that the shield absolutely prevents any contamination of the beer from the materials which might be used in the bung. In addition it will be seen that with the method of removal provided, there is no danger 50 of any foreign matter falling into the barrel such as is the case when wooden bungs have to be chipped or bored out. 55

Although only one form of the invention has been shown and described, it is obvious that 60 various changes and modifications may be made without departing from the spirit of the invention, and all of such changes are contemplated as may come within the scope of the claims.

What I claim is:—

1. A bung for sealing a container opening comprising a sleeve of highly ductile and deformable metal of a size to fit the container opening, and means within said sleeve and movable with respect thereto shaped to deform the sleeve into 70 sealing and locking relationship with the container opening when so moved.

2. A bung for sealing a container opening comprising a lead sleeve of a size to fit the container opening, and means within said sleeve and mov- 75

able with respect thereto shaped to deform the sleeve into sealing and locking relationship with the container opening when so moved.

3. A bung for sealing a container opening comprising a sleeve of deformable metal of a size to fit the container opening, and means within said sleeve and movable outwardly with respect thereto shaped to deform the sleeve into sealing and locking relationship with the container opening 10 when so moved.

4. A bung for sealing a container opening wherein said opening has an inner peripheral shoulder comprising a sleeve of deformable metal of a size to fit said opening and to project inwardly beyond said shoulder, and means within said sleeve and movable outwardly with respect thereto shaped to compress the sleeve into sealing relationship against the sides of the opening and to deform the lower portion of the sleeve to locking 20 position beneath said shoulder when said means is so moved.

5. In a container having an opening, a bushing fitted within said opening, and a bung cooperable with said bushing, said bung comprising a sleeve 25 of deformable metal of a size to fit within said bushing and to project inwardly beyond the inner end of the bushing, and means within said sleeve and movable outwardly with respect thereto shaped to compress the sleeve into sealing relationship against the sides of the bushing and to deform the lower portion of the sleeve to locking 30 position beneath the inner end of the bushing.

6. A bung for sealing a container opening, comprising a sleeve of a size to fit the container opening, means within said sleeve and movable with respect thereto shaped to compress the sleeve into sealing relationship with the container opening when so moved, and means for preventing material within the container from contacting said 40 sleeve.

7. A bung for sealing a container opening, comprising a sleeve of a size to fit the container opening, means within said sleeve and movable with respect thereto shaped to compress the sleeve into sealing relationship with the container opening when so moved, and a cup shaped shield fitted on the lower end of said sleeve for preventing material within the container from contacting said sleeve.

8. A bung for sealing a container opening, comprising a sleeve of a size to fit the container opening, means within said sleeve and movable with respect thereto shaped to compress the sleeve into sealing relationship with the container opening when so moved, and a cup shaped shield of aluminum foil fitted on the lower end of said sleeve for preventing material within the container from contacting said sleeve.

9. A bung for sealing a container opening, comprising a sleeve of a size to fit the container opening, means within said sleeve and movable with respect thereto shaped to compress the sleeve into sealing relationship with the container opening when so moved, and a cup shaped shield cast onto the lower end of said sleeve as an integral part thereof for preventing material within the container from contacting said sleeve.

10. A bung for sealing a container opening, comprising a sleeve of deformable metal of a size to fit the container opening, and a screw in direct threaded connection with said sleeve for movement outwardly with respect thereto, said screw

being shaped to deform the sleeve into sealing and locking relationship with the container opening when threaded outwardly.

11. A bung for sealing a container opening, comprising a sleeve of deformable metal of a size to fit the container opening, and a screw in direct threaded connection with said sleeve for movement outwardly with respect thereto, said screw having an inner thread portion projecting laterally beyond other thread portions to deform the 10 sleeve into sealing and locking relationship with the container opening when the screw is threaded outwardly.

12. In a container having an opening, a bushing fitted within said opening, and a bung cooperable with said bushing, said bung comprising a sleeve of deformable metal of a size to fit within said bushing and to project inwardly beyond the inner end of the bushing, and a screw in direct threaded connection with said sleeve for movement outwardly with respect thereto, said screw being shaped to compress the sleeve into sealing relationship against the sides of the bushing and to deform the lower portion of the sleeve to locking 20 position beneath the inner end of the bushing. 25

13. A bung for sealing a container opening wherein said opening is inwardly tapering, comprising a sleeve of deformable metal of a size and shape to fit said opening, and a screw in threaded connection with said sleeve for movement outwardly with respect thereto, said screw being outwardly tapering to deform the sleeve into sealing and locking relationship with the container opening when threaded outwardly. 30

14. A bung for sealing a container opening 35 wherein said opening is inwardly tapering, comprising a sleeve of deformable metal of a size and shape to fit said opening, and a screw in threaded connection with said sleeve for movement outwardly with respect thereto, said screw being outwardly tapering and having an inner thread portion projecting laterally beyond other thread portions to deform the sleeve into sealing and locking relationship with the container opening when the screw is threaded outwardly. 40

15. In a container having an opening, an inwardly tapering bushing fitted within said opening, and a bung cooperable with said bushing, said bung comprising a sleeve of deformable metal of a size to fit within said bushing and to project inwardly beyond the inner end of the bushing, and a screw in threaded connection with said sleeve for movement outwardly with respect thereto, said screw being outwardly tapering to press the sleeve into sealing relationship against the sides 55 of the bushing when threaded outwardly. 45

16. In a container having an opening, an inwardly tapering bushing fitted within said opening, and a bung cooperable with said bushing, said bung comprising a sleeve of deformable metal 60 of a size to fit within said bushing and to project inwardly beyond the inner end of the bushing, and a screw in threaded connection with said sleeve for movement outwardly with respect thereto, said screw having an inner thread portion projecting laterally beyond other thread portions and being outwardly tapering to compress the sleeve into sealing relationship against the sides of a bushing and to deform the lower portion of the sleeve to locking position beneath 70 the inner end of the bushing. 65

WILLIAM LAUBER.
